TOY AIRPORT STRUCTURE

Ernest L. Thornell, Horicon, Wis., assignor to Marlin
Toy Products, Inc., Horicon, Wis.

Filed Feb. 17, 1971, Ser. No. 116,294

Term of patent 14 years

Int. Cl. D21—01

U.S. Cl. D34—15

Fig. 2.

Fig. 3.

FIG. 1 is a perspective view of a toy airport structure embodying my new and ornamental design;

FIG. 2 is a rear elevation of the same; and

FIG. 3 is a top plan view of the same.

I claim:

The ornamental design for a toy airport structure, as shown.
